DECALCOMANIA PAPER

Henry Atwater, Bryn Mawr, Pa., assignor to
McLaurin-Jones Co., Brookfield, Mass., a cor-
poration of Massachusetts

Application February 11, 1933, Serial No. 656,312

8 Claims. (Cl. 41—33)

This invention relates to decalcomania papers.

Such a paper as usually made heretofore comprises a relatively substantial sheet of backing paper coated on one side with an adhesive which is adapted to take printing ink. Frequently the adhesive coating is not entirely homogeneous but the layer next to the paper is more readily softened than is the outer layer or layers so that the latter can more easily be separated from the backing sheet. In some cases also the adhesive layer includes other constituents in order to produce special results. For example, it may contain metal powders, pigments, or the like, in order to make this coating substantially opaque. Sometimes also the adhesive coating carries a thin film of some water insoluble material such as lacquer, cellulose nitrate, or the like, on which the printing operation will be performed.

In printing the decalcomania design on such papers it usually is necessary to repeat the printing operation one or more times in order to apply the necessary thickness of ink. As a general rule the ink only is transferred to the work and it is therefore necessary that this ink shall be present in a fairly thick body. For the purpose of reducing the number of these printing operations so far as possible, it is customary to apply the ink heavily in each printing operation, and due to this fact there is a very serious tendency for the ink to "offset" or, in other words, to stick to the surface of the next adjacent sheet as the sheets are stacked up in coming from the printing press. While it has been attempted to minimize this difficulty by using driers in the surface of the adhesive coating of the decalcomania paper, and by various other expedients, nevertheless this is still a serious practical difficulty, and it is almost the universal custom to place a sheet of waxed paper or of paper treated in some other suitable manner between each adjacent pair of printed sheets in connection with the stacking operation, these so-called "slip sheets" or "interleaved sheets" remaining in place until after the ink has dried. This operation is commonly called "slip sheeting", and it involves the expenditure of a substantial amount of time, labor and material, all of which tend to increase the manufacturing expense of the printed decalcomanias.

The present invention deals with these considerations. It aims so to improve decalcomania papers and the methods of making them that the necessity for slip sheeting will be avoided.

The nature of the invention will be readily understood from the following description when read in connection with the accompanying draw-

ing, and the novel features will be particularly pointed out in the appended claims.

In the drawing,

Figure 1 is a perspective view, illustrating one embodiment of the invention; and

Figure 2 is a vertical, transverse, sectional view through the sheets illustrated in Fig. 1.

The decalcomania sheets shown in the drawing each includes a backing sheet 2 usually consisting of a fairly heavy sheet of paper containing relatively little sizing so that it readily absorbs water. One face of each sheet carries a coating 3, the surface of which is adapted to take decalcomania printing. This coating may be of any suitable nature, such, for example, as any of those above described. It should, however, be bonded to the backing sheet by a union which can readily be dissolved in water or easily broken so that the backing sheet can easily be stripped from the coating. In a typical case the inner layer of adhesive consists of a mixture of starch and dextrose. So far as these features are concerned the prior practice may be followed since the present invention is not especially concerned with them.

As above stated, this invention deals more especially with the problem of preventing the "offsetting" of the printing ink in connection with the printing process, or, in other words, with the transfer of the ink from the printed face of one sheet to the back of the next adjacent sheet. The invention contemplates that this object can be realized by so roughening the rear face of the backing sheet 2, or, in other words, that face opposite to the adhesively coated face 3, that when the sheets are stacked, no substantial area of one sheet will come in contact with that of the next adjacent sheet. This result may be produced in several ways.

The preferred method consists in embossing the rear surface of the backing sheet with some design which will produce a multiplicity of raised portions distributed substantially uniformly over the surface of the sheet, said portions being separated by intervening lower areas. Such projections or raised portions are indicated at 4 on the lower sheet in Figs. 1 and 2. This embossing operation can be performed by running the sheets of paper, either before or after the gumming operation, between steel rolls, one of which is engraved while the other is smooth. The engraved roll engages the rear face of the backing sheet 2 and produces the roughened effect while the smooth faced roll runs on the front face of the sheet so that this face will be left smooth to re-

ceive the printing. Any design having raised portions which will hold an adjacent sheet away from the main body of the backing sheet will serve this purpose.

- 5 5. A further difficulty involved in the offsetting action above described is the fact that some times the fiber from the back of the sheet sticks to the inked surface. This difficulty can be minimized to a substantial degree by calendering the rear 10 surface of the sheet before it is embossed. This 15 tendency, however, should be borne in mind in selecting the design used in performing the embossing operation, care being taken to have the 20 projections or raised portions located sufficiently close to each other to give adequate support and to provide the necessary area. Designs similar to 25 those used in imitating artificial leathers, coarse fabrics, and the like, have been used with satisfactory results. The upper sheet shown in Figs. 1 and 30 2 is like the lower sheet except that the raised portions 5 are not as well defined as are the projections 4 and are not regular in size or spacing.
- This method of manufacture can be performed 35 at an entirely reasonable expense. It produces an article in which the points of contact of the 40 printed face of a sheet with the back of the next adjacent sheet are so scattered and their total area is so small that no substantial transfer of ink from the printed face of the sheet occurs.
- 30 It does not materially reduce the water absorbing properties of the backing sheet. I have demonstrated by actual use that this invention makes it possible to do away with the slip sheeting heretofore required, while at the same time permitting 35 the application of ink in as large quantities as has been customary even when the practice of slip sheeting has been followed.

In making decalcomania paper by either of the methods above described, it is preferable to use 40 a dryer in the surface coating of gum to which the printing ink will adhere, as has been proposed heretofore, so as to speed up the drying of the ink, so far as possible. The drying operation also is 45 facilitated by the fact that the greater part of the inked surface is spaced from the back of the next adjacent sheet.

While I have herein shown and described a preferred embodiment of my invention, it will be understood that the invention may be embodied 50 in other forms without departing from the spirit or scope thereof.

Having thus described my invention, what I desire to claim as new is:

1. A decalcomania paper comprising a backing 5 sheet of water absorbent paper carrying a coating on one face thereof adapted to take decalcomania printing and bonded to said sheet by a water soluble adhesive, the latter face of said backing sheet being smooth and the opposite face being 10 provided with a multiplicity of raised elements, composed essentially of cellulosic material, distributed over the surface thereof and serving to hold the inked surface of a superposed sheet away 15 from the main body of said backing sheet.
- 65 2. That improvement in methods of making decalcomania paper which consists in applying to the surface of a backing sheet of paper a coating

readily separable from the backing sheet and adapted to take decalcomania printing, and at some stage in the process of manufacture producing, in the material of the sheet, a multiplicity of raised portions on the surface of said 5 backing sheet opposite to said coating while leaving the coated side of the sheet smooth, said raised portions being of sufficient height and so distributed as to hold the inked surface of a superposed sheet away from the main body of said 10 backing sheet.

3. A decalcomania paper comprising a backing sheet having a smooth face carrying a coating adapted to take decalcomania printing, the opposite side of said sheet being roughened substantially throughout the region opposed to said 15 coated surface, said backing sheet and said roughened surface having high water absorbing properties.

4. A decalcomania paper comprising a backing 20 sheet having a smooth face on one side and carrying on said side a coating adapted to take decalcomania printing, the opposite side of said sheet having the material thereof roughened to present definite projecting areas spaced apart by 25 intervening lower areas.

5. A decalcomania paper comprising a backing sheet of water absorbent paper, having a smooth face carrying a coating adapted to take decalcomania printing, said coating being bonded to 30 said sheet by a water soluble adhesive, the opposite side of said sheet having a surface characterized by the presence of a multiplicity of raised portions, integral with said sheet, projecting substantially beyond adjacent areas of 35 said surface.

6. A decalcomania paper comprising a backing sheet carrying on one side thereof a coating adapted to take decalcomania printing, the latter side of said sheet being smooth and the opposite surface of said sheet being embossed to provide a multiplicity of raised portions distributed over the surface thereof and separated by intervening lower areas.

7. That improvement in methods of making 45 decalcomania paper which consists in applying to the surface of a backing sheet of paper a coating readily separable from the backing sheet and adapted to take decalcomania printing, at some stage in the process of manufacture embossing 50 the surface only of said backing sheet opposite to said coating, and producing by said embossing operation raised portions in said sheet of sufficient height and so distributed as to hold the inked surface of a superposed sheet away from the main 55 body of the backing sheet.

8. A decalcomania paper comprising a backing sheet of water absorbent paper, having a smooth face carrying a coating adapted to take decalcomania printing, said coating being bonded to said 60 sheet by a water soluble adhesive, the opposite side of said sheet having a surface characterized by the presence of a multiplicity of projections having relatively small top areas and extending from said surface, said projections having high 65 water absorbing properties.

HENRY ATWATER.
